Patented Apr. 19, 1966

204,524

HAND FIN FOR SWIMMERS

Francis C. Engler, 2821 Dove St., San Diego, Calif.

Filed Apr. 27, 1965, Ser. No. 84,986

Term of patent 14 years

(Cl. D71—1)

FIGURE 1 is a view from the underside of the fin,

I claim:

The ornamental design for a hand fin for swimmers, as shown.
